UNITED STATES PATENT OFFICE.

PETER BROWN, OF HAMPTON, VIRGINIA.

ICE-CREAM-CONE CARRIER.

1,427,440.

Specification of Letters Patent. Patented Aug. 29, 1922.

Application filed November 18, 1920. Serial No. 424,981.

To all whom it may concern:

Be it known that I, PETER BROWN, a citizen of the United States, residing at Hampton, in the county of Elizabeth City and State 5 of Virginia, have invented certain new and useful Improvements in Ice-Cream-Cone Carriers; and I do declare the following to be a full, clear, and exact description of the invention, such as will enable others skilled 10 in the art to which it appertains to make and use the same.

This invention relates to improvements in article carriers, and it has more particular reference to ice-cream cone carriers.

15 The primary object of the invention is to provide a device of the above-mentioned character which is extremely simple in construction which is especially designed to carry a plurality of ice-cream cones in a 20 clean, sanitary and safe condition.

Other objects and advantages of the invention may become apparent during the course of the following description.

In the accompanying drawings forming 25 a part of this specification and in which like numerals are employed to designate like parts throughout the same;

Figure 1 is a plan of a carrier constructed in accordance with my invention.

30 Fig. 2 is an elevational view of the carrier, illustrating the manner in which the cones are placed therein.

Fig. 3 is a horizontal sectional view.

Fig. 4 is a modified form of my invention.

In the drawings, wherein for the purpose of illustration is shown a preferred embodiment of my invention, the numeral 1 indicates of the carrier as a whole which is constructed of a blank sheet 2 shaped as shown in Fig. 1 and having a cover or lid 3 formed thereon. This blank may be of any suitable flexible material, but to make it extremely inexpensive I preferably use suitable substantially tough paper. The surface of the blank 2 is provided or has cut therein at spaced intervals, a plurality of pairs of slits, arranged one above the other. With this arrangement it will be seen that a plurality of strips 4 will be had which are adapted to partially encircle and hold ice-cream cones C in the container 1. In order to permit the container to be easily carried I provide a strip of suitable material 5 which is detachably connected to the blank 2 by a metal fastener as at 6. The opposite

end of the strip is also provided with a similar fastener 7 which is adapted to enter perforations 8 and 9 in the upper corners of the blank and hold it in a rolled position. 60

In forming the carrier so that it may be effectively used, the edges 10 and 11 of the blank 2 are brought together in overlapping relationship and the fastener inserted through perforations 8 and 9 which thus 65 forms a conical-shaped receptacle as shown in Fig. 2. It is to be mentioned here that the strip 5 not only serves as a handle, but also serves as a means for holding the flexible material in conical form. When in this 70 position the ice-cream cones C are placed within the conical receptacle, the smaller ends thereof being passed through the pairs of slits, so that the strips 4 between the slits encircle the body of the ice-cream cones C 75 in the manner clearly illustrated in Fig. 3. The cover 3 is then folded over the tops of the cones, which protects the same and insures a clean and sanitary receptacle.

In the modification shown in Fig. 4, it 80 will be seen that instead of cutting slits in the paper blank 2, I provide strips 13 of suitable material, such as tape, wire, paper or the like, which are arranged one above the other and secured to the blank 2. These 85 strips 13 may be secured to the blank 2 in any suitable manner, such as for instance by paper fasteners 14.

It will thus be seen that the cones which are usually of a brittle nature are conveniently carried in a separated condition, the extreme top portion of the same being the only parts which contact each other. 90

By means of such a carrier cones can be carried a considerable distance without 95 breakage and in a clean and sanitary condition.

It is to be understood that the form of my invention herein shown and described is to be taken as a preferred example of the 100 same, and that various changes in the shape, size and arrangement of parts may be resorted to without departing from the spirit of the invention or of the subjoined claims.

Having thus described my invention, I 105 claim:

1. An ice cream cone carrier formed from a piece of flexible material rolled into conical shape, means for securing and holding said material in said conical shape, said flexible piece of material having cut therein at intervals a plurality of pairs of slits, one 110

- pair of slits being arranged above the other pair to form upper and lower strips which are designed to partially surround an ice cream cone, and a handle for said carrier.
5. 2. An ice-cream cone carrier including a conical shaped receptacle formed of flexible material and having therein a plurality of strips, one strip being disposed above the other to partially encompass and hold ice-
10 cream cones.
3. An ice cream cone carrier comprising a container provided with a plurality of bowed strips for partially surrounding a cone and holding it in place against the
15 body of the container.
4. The structure set forth in claim 3, said

strips being integral with and struck inwardly from the material from which the container is formed.

5. An ice cream cone carrier comprising 20 a substantially conical container formed from a sheet of flexible material, the latter being provided with a plurality of internal flexible bands for partially surrounding cones and holding the latter against the 25 inner wall of the container, said wall being sufficiently flexible to approximately conform to the portion of the cone which bears against it.

In testimony whereof I have hereunto set 30 my hand.

PETER BROWN.
